UNITED STATES PATENT OFFICE.

GEORGE E. COX, OF NIAGARA FALLS, NEW YORK, ASSIGNOR TO AMERICAN CYANAMID COMPANY, OF NEW YORK, N. Y., A CORPORATION OF MAINE.

METHOD OF MAKING CALCIUM CYANAMID.

1,282,381.

Specification of Letters Patent. Patented Oct. 22, 1918.

Application filed December 3, 1917. Serial No. 205,218.

To all whom it may concern:

Be it known that I, GEORGE E. Cox, a citizen of the United States, residing at Niagara Falls, in the county of Niagara 5 and State of New York, have invented certain new and useful Improvements in Methods of Making Calcium Cyanamid; and I do hereby declare the following to be a full, clear, and exact description of the invention, such as will enable others skilled in the art to which it appertains to make and use the same.

This invention relates to a process of improving the grade and reducing the consumption of raw materials in the manufacture of commercial calcium cyanamid and has for its object to accomplish these results in a manner more simple and efficient than has been heretofore proposed.

20 To these ends the invention consists in the novel steps constituting my process, as will be more fully hereinafter disclosed and particularly pointed out in the claim.

Referring to the accompanying drawing, 25 forming a part of this specification, the figure is a diagrammatic illustration of an apparatus suitable for carrying out the invention.

In order that the precise invention may 30 be the more clearly understood it is said:— Outside the United States it has heretofore been customary in making calcium cyanamid from calcium carbide to finely divide the carbide as by grinding, to fill with the ground 35 carbide at the grinding apparatus, suitable combustible inner containers held in strong perforated outer containers, and to transport said filled containers for a distance of say several hundred feet to the nitrifying 40 ovens, and to then place said filled outer and inner containers inside said ovens.

In bringing about the reaction between the nitrogen present and the finely ground carbide, it is of course very desirable, indeed, 45 that the nitrogen thoroughly permeate the interstices between the dust like particles of carbide for otherwise an efficient nitrification of the carbide is not had.

I have discovered through repeated tests 50 that the best results are not attained by following the above mentioned customary practice of charging the finely ground carbide into its suitably lined outer container by the usual procedure of standing the container under the silo holding the ground carbide and filling the same.

It seems that the handling of the can over only a few hundred feet by the usual transport devices of trucks, cranes, etc., probably alters the physical condition of the mass of carbide, so that by the time it has been transported from the silo in the vicinity of the grinding equipment to the apparatus for treating the carbide with nitrogen, the interstices between the particles have been partially closed, or the physical condition has otherwise suffered so much that one does not obtain the best results in the subsequent treatment.

It has not proven advantageous in practice, to build the grinding and carbide storage equipment in close proximity to all of the many units required for nitrification, and therefore, it is a universal practice to transfer by means of trucks, and cranes, the loaded container to the nitrifying apparatus, and to lower it to its place inside the same.

My invention is designed to eliminate the above mentioned disadvantages incident to this method of transporting of the carbide from the place of storage to the furnace where it is nitrified in the manner now to be disclosed. In said drawings, "A" represents the outer wall of a nitrifying furnace 80 or oven, "B" a cover for said oven, "C" a refractory lining for the oven, "D" an inlet for nitrogen, "E" a resistor, "F" and "G" suitable insulation for said resistor, "H" an outer container provided with an inner container or lining, both of which have been, according to practice heretofore, filled with finely ground carbide "L" at the grinding apparatus, instead of at the oven, and "M" the usual space for the nitrogen between the 90 container "H" and the lining "C."

In carrying out this invention, I provide the container "H" with its combustible, textile or other envelop or lining and insert the same empty into the furnace "A". I load 100 the carbide into a suitable closed transporting device, not shown, provided with means for discharging the carbide from its bottom. This transport container is then picked up by the truck, crane or other device and 105 moved to a point immediately over the furnace. It is then lowered inside said envelop and container close to the bottom of the same. The carbide held by the transport container is then discharged through its bottom opening 110 into the said envelop and at the same time the transport container is slightly raised so

that the mass of carbid "L" during the filling operation drops through only a very short free space into the final furnace container "H" and has its interstices, or pores opened 5 to a maximum extent.

This method of filling the empty nitrifying containers "H" after they are in place in the furnace therefore results in very much greater porosity, in the mass, and the efficiency of the nitrification of the carbid as is evidenced by the results obtained. 10

That is to say, experiments carried out on an extended manufacturing scale showed that in Experiment 1, where 17 full sized 15 commercial units "H" were filled while in the ovens "A" as compared with 24 containers filled outside the ovens by the old method, and then transported to the ovens, all charged with identically the same material and nitrified in identically the same type 20 of furnace, and under the same conditions, the fixation of nitrogen was 2.8% better, and the percentage of efficiency with which the carbid was utilized, 3.3% better in favor of the 25 containers "H" charged with carbid while in the furnace "A".

In Experiment 2, where 24 containers "H" were loaded by the old practice, and 29 by the method disclosed in this specification, the 30 figures show respectively 2.5% greater in nitrogen content, 40% lower in remaining unnitrified carbid and 4% greater in carbid utilization efficiency in favor of the containers filled inside the ovens.

35 In Experiment 3, where 12 containers were loaded by the old method and transferred to the ovens and 10 containers were

charged in place in the ovens the figures were 2.7% greater nitrogen fixation, 7% lower in unnitrified carbid and 3½% greater 40 carbid efficiency in favor of the containers loaded in the ovens. This new process of container loading has also shown consistently better results in the quality of the product made, it being higher in nitrogen 45 and lower in remaining unnitrified carbid, and it also shows a much better utilization of the calcium carbid consumed in the process.

It is self evident that those skilled in the art may vary the above procedure without departing from the spirit of the invention, and therefore, I do not wish to be limited to the above disclosure except as may be required by the claim. 55

What I claim is:

The process of producing compounds of carbids and nitrogen which consists in providing a suitable container for carrying on the reaction; inserting said container into the furnace in which said reaction is to be completed; charging said carbid in a finely divided condition into said container in place; and subjecting said mass of charged carbid to the requisite temperature in the presence of nitrogen to form said compounds, substantially as described. 60 65

In testimony whereof I affix my signature in presence of two witnesses.

GEORGE E. COX.
